Primary Examiner — Joseph Kukella

Assistant Examiner — Laron M. Amerson

(57) **CLAIM**

The ornamental design for electric bicycle, as shown and described.

DESCRIPTION

FIG. 1 is a front perspective view of electric bicycle, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 1;

FIG. 10 is an enlarged detail view of area 10 in FIG. 1;

FIG. 11 is an enlarged detail view of area 11 in FIG. 1;

FIG. 12 is an enlarged detail view of area 12 in FIG. 1;

FIG. 13 is an enlarged detail view of area 13 in FIG. 1;

FIG. 14 is an enlarged detail view of area 14 in FIG. 2; and,

FIG. 15 is an enlarged detail view of area 15 in FIG. 2.

The long dash-short dash broken lines in FIGS. 1, 2, 9, 10, 11, 12, 13, 14 and 15 show the boundaries of the enlargements shown in FIGS. 9, 10, 11, 12, 13, 14 and 15, and form no part of the claimed design.

1 Claim, 15 Drawing Sheets
